Primary Examiner — Michael A. Pratt*Assistant Examiner* — Wendy Arminio(74) *Attorney, Agent, or Firm* — The Van Winkle Law Firm; William G. Heedy(57) **CLAIM**

The ornamental design for a bottle closure, as shown.

DESCRIPTION

FIG. 1 is an upper perspective view of a bottle closure of our new design;

FIG. 2 is another upper perspective view of the closure of FIG. 1, rotated from the view of FIG. 1;

FIG. 3 is a perspective view of the underside of the closure of FIG. 1;

FIG. 4 is another perspective view of the underside of the closure of FIG. 1, rotated from the view of FIG. 3;

FIG. 5 is a side elevation view of the closure of FIG. 1;

FIG. 6 is an opposite side elevation view of the closure of FIG. 1;

FIG. 7 is a top plan view of the closure of FIG. 1; and,

FIG. 8 is a bottom plan view of the closure of FIG. 1.

1 Claim, 8 Drawing Sheets(56)
